UNITED STATES PATENT OFFICE.

FREDERICK C. WILCOX, OF KEENE, NEW HAMPSHIRE.

DESIGN FOR A RADIO PHONE HOLDER OR SIMILAR ARTICLE.

Application filed May 12, 1927. Serial No. 21,949. Term of patent 3½ years.

To all whom it may concern:

Be it known that I, FREDERICK C. WILCOX, a citizen of the United States of America, residing at Keene, in the county of Cheshire and State of New Hampshire, have invented a new, original, and ornamental Design for a Radio Phone Holder or Similar Article, of which the following is a specification, reference being had to the accompanying drawing, forming a part thereof.

In said drawing:

Fig. 1 is a front elevation of a radio phone holder showing my new design; and Fig. 2 is a side view thereof.

I claim:

The ornamental design for a radio phone holder or similar article substantially as shown.

Signed by me at Keene, in the county of Cheshire and State of New Hampshire, this ninth day of May, 1927.

FREDERICK C. WILCOX.
